ARTHUR MORTON, OF WARWICK, RHODE ISLAND, ASSIGNOR TO CROMPTON COMPANY,
OF PROVIDENCE, RHODE ISLAND, A CORPORATION OF RHODE ISLAND.

PILE-CUTTING MACHINE.

1,082,894.

Specification of Letters Patent. Patented Dec. 30, 1913.

Application filed August 10, 1907, Serial No. 387,960. Renewed February 7, 1913. Serial No. 746,922.

To all whom it may concern:

Be it known that I, ARTHUR MORTON, of Warwick, in the county of Kent and State of Rhode Island, have invented certain new and useful Improvements in Pile-Cutting Machines; and I do hereby declare the following specification, taken in connection with the accompanying drawings, forming a part of the same, to be a full, clear, and 10 exact description thereof.

In a pending application, Serial No. 368,329, I have shown and described a pile cutting machine which is adapted for the cutting of velvets, which machine, however, 15 is not entirely automatic, for the reason that the knife is not a part of the machine, but requires to be held and manipulated by the operator during the operation of cutting the races of the fabric.

20 The object of the present invention is to provide a machine which is adapted for the cutting of velvets, and which will be entirely automatic in its operation.

To that end the invention consists primarily in mounting the knife on, and making it a part of, the machine, as distinguished from having the knife held and manipulated by the operator.

The invention further consists in so 30 mounting the knife as a part of the machine that the knife will be free to follow any irregularities of the races, and thus be capable of performing its work without the assistance or guidance of an operator.

35 The invention further consists in providing means whereby a certain forward and backward yielding of the knife will be permitted according to the thrust exerted upon it by the fabric during the operation of cutting, and so that there will be more or less of a give and take movement of the knife according to the varying conditions presented.

The invention further consists in providing 45 means whereby, if the knife shall fly out of the race, the point of the knife will be moved to a position above that portion of the fabric which has been already cut, and where no harm can result if the knife 50 should come in contact with the fabric at that point.

The invention further consists in the combination, with the knife, of a stop motion adapted to be automatically operated by 55 the knife to stop the machine, in case the

knife should happen to fly out of the race or to penetrate the back of the fabric, or become otherwise disarranged.

The invention further consists in the combination of two stop motions for stopping 60 the machine, one adapted to be operated by the knife and the other adapted to be operated by the bunch or seam in the endless fabric.

The invention further consists in the combination of means for operating either the main forward clutch or the reversing clutch, and means for determining which of these two clutches shall be operated thereby.

The invention further consists in certain 70 combinations and arrangements of parts hereinafter described and claimed.

Referring to the drawings, Figure 1 is a side elevation of the machine. Fig. 2 is a side elevation on a larger scale of the forward end of the machine taken from the opposite side, the traveling apron at the bottom of the machine being omitted and the fabric being shown only in part. Fig. 3 is a broken end elevation of the front end 80 of the machine. Fig. 4 is a section through the machine on the line $\alpha-\alpha$ of Fig. 1 looking toward the front of the machine. Figs. 5 and 6 are details. Figs. 7 and 8 are front and rear elevations, and Figs. 9 and 10 are 85 opposite end elevations of the knife-holder mounted on its supporting arbor. Figs. 11, 12, 13, 14 and 15 are details of the knife-holder and its component parts. Fig. 16 is a view corresponding to Fig. 10, but on a 90 smaller scale and showing the knife-arm mounted in the knife-holder.

The machine comprises a suitable frame 1, in which the several operating parts are mounted. The fabric travels through the 95 machine in the form of an endless web. The knife 2 is located at the front of the machine, and the fabric 3, after the race has been cut, is carried down on to a traveling endless apron or lattice 4 at or near the 100 bottom of the machine, where it drops in folds, and in this form is carried by the traveling apron to the rear of the machine. From the apron at the rear of the machine the fabric is carried up over a feed-roll 5 and 105 down an incline 6. At the foot of this incline the fabric turns upward and is carried over two fixed bars 7, 7 at the top of the frame. Preferably the fabric is left more or less loose at the point where its di- 110

rection is changed from the foot of the incline to the vertical.

From the stationary bars 7, 7, the fabric travels down another incline 8, around an idler-roll 9, up over a belt driven roll 10, preferably rubber-covered, down around another idler roll 11, then forward around a tension-roll 12, which is also an idler roll and around the drag-roll 13. In my former machine the fabric was passed directly from the drag-roll to the feed-roll. In the present machine, however, the fabric, instead of being thus passed directly to the feed-roll, is passed around two intermediate idler-rolls 13^a, 13^b, and thence to the feed-roll 14. As will be seen, by the employment of the two idler rolls 13^a, 13^b, arranged as shown in the drawings, in connection with the tension-roll 12, the fabric is caused to extend around nearly the entire periphery of the drag-roll 13, thereby increasing the friction between the fabric and said roll, and enabling said roll to be a plain steel roll, instead of a rubber-covered roll. The roll 13^b also serves to locate the fabric for presentation to the knife.

In passing from the idler-roll 13^b to the feed-roll 14 the fabric passes beneath the knife 2. From the feed-roll 14 the fabric passes to the tension-roll 15, thence downward between a pair of supplemental feed-rolls 16, 17, the feed-roll 16 being belt-driven, and the feed-roll 17 being an idler-roll, and thence down on to the traveling apron 4 above referred to.

The necessary tension at the cutting point is produced by means of the rolls 13 and 14. The feed-roll 14 is positively driven, while the drag-roll 13 is provided with a friction device whereby a friction or drag may be put on said roll.

The main driving shaft 19 is provided with a pulley 20 driven by a belt 21 from an over-head counter-shaft. On the opposite end of the driving shaft 19 is a pulley 22, from which a belt 23 extends to a pulley 24 on the left hand end of the positively driven feed-roll 14. On the driving shaft 19, adjacent to the main driving pulley 20, is a pulley 25, from which a cross-belt 26 extends to a loose pulley 27 on the feed-roll 14. The pulley 27 is a two-step cone-pulley, and from the smaller step of said pulley a belt 28 extends to a pulley 29 on the right hand end of the drag-roll 13.

In the present machine the drag-roll 13, instead of being of the same diameter as the feed-roll 14, is of considerably larger diameter, and as said drag-roll becomes a feed-roll for the reverse feed, it is desirable to correspondingly reduce the speed of said drag-roll 13 when operating as a feed-roll during the reverse feed, and for this purpose the step of the pulley 27 over which the belt 26 passes is of considerably larger diameter

than the pulley 25, and the pulley 29 on the drag-roll 13 is also considerably larger than the smaller step of the pulley 27 over which the belt 28 passes.

On the left hand end of the drag-roll 13 are two pulleys 30 and 31, as shown in Fig. 2. From the pulley 30 a belt 32 extends around a pulley 33 on the left hand end of the supplemental feed-roll 16. From the pulley 31 a belt 34 extends to a pulley 35 on the left hand end of the roll 10. On the right hand end of said roll 10 are two pulleys 36 and 37. From the pulley 36 a belt 38 extends to a pulley 39 on the right hand end of the feed-roll 5. From the pulley 37 a belt 40 extends to a pulley 41 on a stud 42, on which stud is a second pulley 43 connected to said pulley 41, and from which pulley 43 a cross-belt 44 extends to a pulley 45 on a shaft 46 at the rear end of the machine. Said shaft 46 is the feed-shaft for the endless traveling apron 4. In the drawings a belt-tightener 40^a is shown for tightening the belt 40.

The pulley 22 on the driving shaft 19 is loose on said shaft, but is adapted to be connected with said shaft by a suitable clutch mechanism, preferably a friction-clutch as shown in the drawings. This clutch may be of any desired construction, and as it forms no part of the present invention, the detailed construction of the clutch shown need not be described. It will be understood that when the pulley 22 is connected with the driving-shaft 19, the fabric will be fed through the machine, and when the pulley 22 is disconnected from the shaft 19, the feed of the fabric will be stopped. The clutch mechanism as a whole is designated as 47 in the drawings, and said clutch mechanism is adapted to be operated by the lever 48.

In machines of this character it is desirable that when the driving power is disconnected for the purpose of stopping the machine, the machine should be quickly brought to a full stop, and so as to promptly stop the feed of the fabric. For this purpose a brake-mechanism is applied to some part of the feed mechanism to quickly stop the feed of the fabric whenever the driving power is disconnected.

In the arrangement shown the brake is applied to the drag-roll 13, or rather to the pulley 30 on said roll. This brake may be of any suitable construction, and in the drawings is shown as comprising a brake-shoe 49 pivoted to a bracket secured to the frame, which brake-shoe is adapted to be forced into contact with the inner surface of the flange of the pulley 30 by means of a coil-spring 50.

The brake-shoe 49 is normally, or while the machine is in operation, latched out of contact with the pulley-flange. Connected

to the free end of the brake-shoe is a vertical bar 51 which extends downward and is supported and guided by a bracket 52 extending from the frame of the machine. 5 Adjustably secured to one side of this bar 51 is a notched block 53 adapted to engage, or be engaged by, the forward end of a movable bar 54. One end of the spring 50 is connected to said bar 51, the other end of 10 said spring being connected to a bracket 55 on the frame. When the machine is running the bar 51 is latched and held in its upper position, and so as to hold the brake-shoe 49 out of contact with the flange of 15 the pulley 30 by the end of the movable bar 54 engaging the notched block 53. When, however, said movable bar 54 is moved rearward by any suitable means, the bar 51 is thereby disengaged and is pulled downward 20 by the spring 50, thereby forcing the brake-shoe into contact with the flange of the pulley 30 and stopping the feed of the fabric. In the machine shown means are provided for automatically throwing out the clutch 25 47 and for automatically applying the brake 49, which means will be hereinafter described.

The means for releasing the brake and starting the machine to feed forward the 30 fabric after the machine has been stopped and the brake applied will be next described. A foot-treadle 56 extends across the front of the machine where it may be conveniently operated. This treadle is secured by 35 means of arms 57, one on each side of the machine, to a rock-shaft 58, which extends across the machine and is arranged to turn in bearings in the frame. Connected to this rock-shaft are two weights 59, one on 40 each side of the machine, which act to normally hold the treadle 56 in its upper position. Secured to the rock-shaft 58 is an arm 60, to which is connected one end of a connecting rod 61, the other end of which 45 is connected to one arm of a bell-crank lever 62 which is pivoted on the frame, as shown in Fig. 2. The other arm of this bell-crank lever is provided with a friction-roll 63, which underlies the lower end of the 50 vertical bar 51 which is connected to the brake-shoe. When the bell-crank lever 62 is rocked, by depressing the treadle 56, one result will be to lift the brake-shoe 49 out of contact with the flange of the pulley 30 and thus release the brake.

Connected to the arm of the bell-crank lever 62, to which the rod 61 is connected, is another connecting rod 64, the opposite end of which is connected to an arm 65 secured 60 to a rock-shaft 66 mounted in brackets secured to the frame of the machine. In the present machine the reversing clutch to be hereinafter referred to is also operated by the foot-treadle 56, and for this reason the 65 connection between the arm 65 and the

clutch-lever 48, instead of being a permanent connection, is made detachable, but when the connection between said arms 65 and 48 is made and the treadle 56 is depressed, the further result will be that the 70 arm 65 will be rocked, and this in turn will serve to pull inward the lower end of the clutch-lever 48, and thus throw in the clutch 47 and connect the pulley 22 to the driving shaft 19.

Pivoted to the clutch-lever 48 is a latch-bar 68 provided with a shoulder 69 adapted to engage the bracket 70, through a slot in which bracket the end of the latch-bar 68 extends. When the clutch 47 is thrown in 80 to connect the pulley 22 with the shaft 19, the upper end of the clutch-lever 48 is moved away from the bracket 70, and so as to draw the latch-bar 68 outward and into a position where the shoulder 69 on said 85 latch-bar will engage said bracket, and thereby latch and hold the clutch in its engaged position. The weight of the latch-bar 68 will ordinarily be sufficient to cause said bar to fall down and engage the latch. 90 If desired, however, a spring may be employed for this purpose.

It is desirable in machines of this character to provide means to reverse the machine and the feed of the fabric, in order 95 that if the knife should fly out of the race, or any other accident happen, the fabric may be run back a short distance for the purpose of reinserting the knife in the race. This reversal of the machine is effected by 100 means of the cross-belt 26 running on one of the steps of the cone-pulley 27 on the feed-roll 14. This cross-belt 26 is driven by the pulley 25, which is loose on the main driving shaft 19, but which is provided with 105 a clutch 71 adapted to be operated by a lever 72 for clutching said pulley to said driving shaft. In the present machine, as hereinbefore stated, this reversing clutch 71, as well as the forward clutch 47, is operated 110 by the foot-treadle 56, said reversing clutch, like the main starting clutch, being operated from the rock-shaft 66, means being provided for determining which of these two clutches will be operated when the foot-treadle 115 is depressed.

Mounted on the rock-shaft 66 is a sliding collar 73 having an arm 74 projecting rearwardly therefrom, which arm carries a vertical rod 75, which rod partakes of the sliding movements of said collar 73. Secured to the rock-shaft 66 are two rearwardly extending arms 76 and 77, which serve as guides for the rod 75 as it is moved upward or downward by said sliding collar. The 120 sliding movements of the collar 73 and the rod 75 are effected by means of a hand-lever 78, pivoted to the frame at the front end of the machine, through the following connections. A bell-crank lever 79 is piv- 130

oted to the frame, the horizontal arm of which lever is provided with a projecting pin 80 adapted to enter a groove in the sliding collar 73. The vertical arm of said bell-crank lever is connected by means of a rod 81 with the lower end of the hand-lever 78.

Connected to the end of the clutch-lever 48 is a latch-bar 82, the free end of which latch-bar is supported by a pin 83 projecting from the frame, which pin extends through a slot in said latch-bar, as shown in Fig. 4. Said latch-bar 82 is provided with a suitable notch to form a shoulder 82^a adapted to be engaged by the upper end of the sliding rod 75. To the lower end of the reversing clutch-lever 72 is connected a latch-bar 84, which extends across the machine, said latch-bar being likewise provided with a suitable shoulder 84^a adapted to be engaged by the lower end of said sliding rod 75. In order to provide for the swinging movement imparted to the sliding-rod 75 by the rocking of the shaft 66, it is desirable to provide a swivel connection between the arm 77 and the latch-bar 84. Loosely mounted in the end of the arm 77 is a hollow stud 85, the lower end of which is forked to receive the end of the latch-bar 84, said latch-bar being connected to the forked end of said stud by means of a cross-pin 85^a. The hollow stud is held in place in the arm 77 by means of a nut 86 which engages the upper end of said stud. As will be understood, the lower end of the sliding rod 75 projects through said hollow stud, and so that the lower end of said rod may be moved into engagement with the shoulder 84^a on the latch-bar 84.

With the construction above described the operation of starting or reversing the machine is as follows: When the hand-lever 78 is pulled forward into the position shown in Fig. 2, the sliding collar 73 and the sliding rod 75 will be moved upward, so as to bring the upper end of said rod into engagement with the shoulder on the latch-bar 82. With the sliding rod held in this position, the foot-treadle is depressed which will serve to turn the rock-shaft 66, thereby giving a swinging movement to the rod 75, which movement will serve to actuate the latch-bar 82 and the clutch-lever 48 to throw the clutch 47 into engagement. When now it is desired to reverse the machine, the hand-lever 78 is thrown backward, which will serve to move the sliding collar and the sliding rod downward, and so as to move the upper end of said rod out of engagement with the latch-bar 82, and to move the lower end of said rod into engagement with the latch-bar 84. By now depressing the foot-treadle, and thereby turning the rock-shaft 66, a swinging movement will be given to the sliding rod 75 which will serve to move

the latch-bar 84 and the lever 72 to throw in the reversing clutch 71. With the position of the parts shown in Fig. 4, both the clutch 47 and the clutch 71 are out of engagement and the machine is at rest. The sliding rod 75, however, is shown in its upper position and in engagement with the latch-bar 82, and so that by the depression of the foot-treadle, the clutch 47 will be thrown into engagement. In order to permit the necessary swinging movement of the rock-shaft 66 to operate the latch-bar 82, without at the same time operating the latch-bar 84, said latch-bar 84 is provided with an elongated slot 84^b through which the cross-pin 85^a passes, as shown in Fig. 4.

As above stated, both of the supplemental feed-rolls 10 and 16 are belt driven rolls, both of said rolls being driven from the drag-roll 13. As shown in the drawings, the pulley 35 on the feed-roll 10 is somewhat larger than the pulley 31 on the drag-roll, and so that said feed-roll will be rotated at a somewhat slower speed than the drag-roll, and will thus serve to put a certain amount of drag on the fabric as it approaches said drag-roll. In the case of the feed-roll 16, however, it is desirable that said roll should rotate at a higher speed than the drag-roll 13, in order to put a pull upon the fabric, and for this purpose the pulley 33 on said roll 16 is shown as considerably smaller than the pulley 30 on the drag-roll.

While it is desirable that the feed-roll 16 should rotate at a higher speed than the drag-roll 13 and the feed-roll 14 during the forward feed of the fabric, it is not desirable that said roll 16 should rotate faster than the feed-roll 14 during the reverse feed of the fabric, because in such case the effect of said roll 16 would be to put slack in the fabric between said roll and the main feed-roll 14, which would be objectionable. In order to prevent such objectionable operation, and also to transform said feed-roll 16 from a roll exerting a forward pull on the fabric to a roll exerting a backward pull on the fabric, the following means are provided.

The pulley 33, instead of being fast on the feed-roll 16, is loose thereon, and adapted to be connected with said roll during the forward feed of the fabric by means of a pawl and ratchet. In the construction shown the ratchet 87 is formed on the pulley 33, and the pawl 88 is carried by the disk 16^a secured to the roll 16, the arrangement of said pawl and ratchet being such that when the drag-roll 13 is rotated to feed the fabric forward the roll 16 will be rotated in the same direction by means of said pawl and ratchet. When, however, the drag-roll is rotated in the backward direction for the reverse feed of the fabric the ratchet-teeth on the pulley will ride under

the pawl carried by the roll, and so that said roll will be free to be turned by the pull of the fabric.

In order to put a drag on the fabric during the reverse feed, it is preferred to provide means for braking the feed-roll 16 during such reverse feed, and in the drawings a brake is provided for this purpose, which brake is adapted to be automatically operated in the following manner: Pivoted to the bracket at the left hand side of the machine in which the feed-roll 16 is mounted is a brake-lever 89, the rear end of which is suitably curved to form a brake 90 adapted to engage the outer surface of a flange 91 formed on the disk 16^a secured to the roll 16. To the forward end of the lever 89 is connected one end of a spring 92, the other end of which spring is attached to the frame or some fixed part of the machine, being shown in the drawings as connected to the pivot of the hand-lever 78, which said spring normally acts to pull down the forward end of the lever 89, and thus to apply the brake 90 to the feed-roll 16. The application of said brake 90 is controlled by the hand-lever 78. The lever 89 lies in the path of a pin 93 projecting horizontally from said lever 78, and said lever 89 is provided with a recess 94, the construction being such that when the hand-lever 78 is pulled forward the forward end of the lever 89 will be held in a raised position by the engagement therewith of the pin 93, but when said lever 78 is thrown rearward the forward end of the lever will, by reason of the recess 94, be pulled downward by the spring 92, thereby automatically applying the brake 90. It is preferred when the lever 78 is pulled forward to latch said lever in its forward position, and for this purpose the lever 89 is provided with another recess or notch 95 adapted to engage the pin 93 when the lever 78 is pulled forward, as shown in Fig. 2.

The machine shown in the drawings is provided with a mechanical stop motion for automatically stopping the machine when the bunch or seam in the endless fabric approaches the knife. As above stated, when the clutch 47 is thrown in, said clutch is latched in engagement by the latch 68 engaging the bracket 70. Connected to the upper end of the clutch-lever 48 is a spring 96, the other end of which spring is connected to a fixed support 96^a. When the clutch-lever 48 is moved to throw in the clutch 49 the spring 96 is put under tension, and will operate whenever the latch 68 is disengaged to automatically throw out said clutch. For the purpose of automatically stopping the machine by the bunch or seam in the fabric, means adapted to be actuated by said bunch are provided for disengaging the latch 68. Extending across the machine above the fabric is a rock-shaft

97 which carries a flat leaf-spring 98, which spring normally lies in engagement with the fabric. The present construction is such that said leaf-spring 98 is located in proximity to the drag-roll 13, and in a position where it engages the fabric as it passes over said drag-roll.

Pivoted to the bracket 99 is a lever 100 provided at one end with a projection 101 adapted to be engaged by a latch formed on the end of the arm 102 carried by the rock-shaft 102^a. The opposite end of said lever 100 is connected by a link 103 with an arm 104 carried by a rock-shaft 105 suitably mounted in fixed supports. The rock-shaft 105 is provided with an upwardly projecting toe 106 arranged to normally underlie one end of a pivoted lever or tappet 107 pivoted on the bar 54. The tappet 107 is provided with a notch 107^a adjacent to the toe 106 when the parts are in normal position. Pivoted on the frame at 108 are two levers 109 arranged side by side. As the construction and operation of these two levers and their connecting and coöperating parts are the same, it will be sufficient to describe the construction and operation of one of said levers. Mounted on the shaft of the driven roll 10 is an eccentric 110 which is connected with the upper end of the lever 109, whereby said lever is vibrated back and forth at each revolution of said shaft. The bar 54 extends lengthwise of the machine, said bar being pivotally connected at one end to the pivoted link 111, and being connected at its other end to one arm of a bell-crank lever 112, which bell-crank lever is adapted to be operated by said bar 54. The tappet 107 pivoted on the bar 54 is normally held in a horizontal position by the engagement therewith of the toe 106, and when thus held in a horizontal position the forward end of said tappet will be out of the path of the vibrating lever 109. The other arm of the bell-crank lever 112 projects through an inclined slot or cam-slot 113 in the latch-bar 68 pivoted to the clutch-lever 48. Connected to the lower end of the arm 102 is a rod 114, the other end of which rod is connected to a lever 115 secured to the rock-shaft 97.

The operation of the automatic stop motion above described is as follows: As the bunch or seam in the fabric passes beneath the spring-arm 98 it will serve to rock the shaft 97, and thereby disengage the latch 102 and release the lever 100. The rear end of said lever 100 is weighted or is sufficiently heavy so that when released by the unlatching of the latch 102 the rear end of said lever will fall downward, thereby raising the forward end of said lever. The raising of the forward end of said lever 100 will, through the link 103 connected to the arm 104 on the rock-shaft 105, serve to rock said

- rock-shaft, which will cause the toe 106 to be moved from beneath the tappet 107, and cause the forward end of said tappet to be moved into the path of the vibrating lever 109. By the action of said lever the bar 54 will be moved rearward, turning the bell-crank lever 112 which, by reason of the cam-slot 113, will serve to unlatch the latch 68 and thereby permit the clutch 47 to be thrown out by the spring 96. The rearward movement of the bar 54 serves to unlatch the bar 51 and thereby cause the brake to be applied by the action of the spring 50.
- 15 The construction and arrangement of the knife-holder, whereby the knife is made a part of the machine, together with an automatic stop motion for automatically stopping the machine when the knife runs out 20 of the race or projects through the back of the fabric, or is otherwise disarranged, will next be described.
- 25 Slidably mounted on the bar 116 which extends across the front of the machine is a sleeve 117, the aperture in which is preferably square in cross-section to fit said bar. Projecting downwardly from said sleeve is a U-shaped bracket 118, in which the knife-holder 119 is pivotally mounted. The knife-holder is composed of two parts, 120 and 121, for a purpose to be hereinafter described, but the knife-holder as a whole is pivoted in the bracket 118, so as to be capable of turning about a horizontal axis.
- 30 35 As shown in the drawings, the part 120 of the knife-holder is mounted between two horizontal screws 122, which screws are preferably provided with conical points adapted to take into corresponding conical recesses formed one on each side of the knife-holder. With this construction the knife-holder is adapted to swing toward and from the front of the machine.
- 40 The part 121 of the knife-holder is provided with an elongated shank 123 provided with two enlargements 123^a and 123^b, and the part 120 being bored and counterbored to receive said shank and enlargements, as shown in Fig. 12. A torsion-spring 124, 45 adapted to surround the shank 123, has two collars 124^a and 124^b secured one to each end of said spring, said collars being adapted to surround the enlargements 123^a and 123^b respectively. The collar 124^b and the shank 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

in Figs. 13 and 14, whereby a slight turning movement of the vertical pivot formed by the shank may be given to the part 121 of the knife-holder by the action of the torsion spring 124. With this construction the part 121 of the knife-holder, when permitted to be acted upon by said spring, will normally stand at a slight angle with relation to the part 120 of said holder.

For the purpose of limiting the extent of the forward and back swinging movements of the knife-holder, an arm 129 is rigidly secured to one of the legs of the bracket 118. The upper end of said arm is provided with a U-shaped slot 130 into which projects the pin 131 projecting from the part 120 of the knife-holder. The engagement of said pin 131 with the opposite walls of the slot 130 serves to limit the forward and back movements of the knife-holder.

Means are provided for automatically swinging the knife-holder backward on its horizontal pivot whenever such movement is permitted, such means comprising a spring-pressed plunger 132, which said plunger is acted upon by a spring 133. It is desirable to adjust the tension of said spring in order to regulate the amount of thrust upon the knife which will serve to overcome the force of said spring, and for this purpose an adjusting screw 134 is provided, which said screw is mounted in an ear 135 projecting downward from the sleeve 117. Said adjusting screw is provided with a shoulder 136 against which one end of the spring 133 abuts. By turning said adjusting screw, therefore, the tension of said spring may be adjusted.

The part 121 of the knife-holder is provided with two transverse slots 137 and 138 arranged at right angles to each other, the slot 137 being adapted to receive the shank of the knife-arm, and the slot 138 being adapted to receive the trunnions or projecting pins 139 on said knife-arm.

The purpose of constructing the knife-holder in two parts, with the part 121 capable of turning on a vertical axis with relation to the part 120 under the action of the spring 124, is to cause the knife-arm and knife, when the knife leaves the race, to be thrown to one side, as for example to the right, and thus above the portion of the fabric which has been already cut. With this construction it is desirable to provide means for conveniently returning the part 121 and the knife-arm and knife carried thereby to their normal positions for the purpose of reentering the knife in the race, and for this purpose the part 121 of the knife-holder is provided with a projecting pin 140 bent to form a cam-surface. Mounted on the sleeve 117 is a second sleeve 141 adapted to have a limited turning movement on the sleeve 117. Said sleeve 141 is

provided with a projecting pin 142 adapted to engage the bent pin or cam-projection 140, and so that by turning said sleeve 141 by hand, the engagement of said pin 142 with said bent pin or cam-projection will serve to turn the part 121 of the knife-holder and the knife-arm carried thereby, and return them to their normal position, where they may be held until the knife has been properly reentered in the race. In order to limit the movement of the sleeve 141 said sleeve is provided with a slot 143, and a pin 144 projecting from the sleeve 117 enters said slot and is adapted to engage the end walls thereof.

In cutting the first race the backward thrust upon the knife is greater than in cutting the successive races in what is known as right-race cutting. For this reason, among others, it is desirable to hold the knife-holder against turning on its horizontal axis toward the front of the machine during the cutting of the first race. For this purpose the following means are provided. The part 120 of the knife-holder is provided on one side at its upper end with an offset 145 in which is formed an inverted V-shaped slot 146. Projecting from the sleeve 141 is a pin 147, the end of which is adapted to enter said slot 146. The parts are so arranged that when the sleeve 141 is turned to bring the part 121 of the knife-holder into proper position for entering the knife in the race, said pin 147 will be moved to the apex of the slot 146, and as long as said sleeve 141 is held in this position the knife-holder will be prevented from turning on its horizontal axis either forward or backward, by reason of the engagement of the pin 147 with the walls of the slot 146 at the apex thereof.

With the above construction whenever the knife flies out of the race the forward thrust of the knife will be relieved, whereupon the spring 133 will act to turn the knife-holder about its horizontal axis toward the rear of the machine. On the other hand, whenever the thrust on the knife is increased sufficiently to overcome the tension of said spring 133, as will be the case, for instance, when the knife projects through the back of the fabric, or when the knife enters a slip race, instead of a right race, the knife-holder will, by such increased thrust, be turned about its horizontal axis toward the front of the machine and against the action of said spring. It is desirable when either of these things happens that the machine shall be stopped, and means are provided for automatically stopping the machine in either case, such means consisting of an electric stop motion which will be next described.

Extending across the machine at the front end and parallel with the bar 116 is a bar

148. As shown in Fig. 2, one wire 149 of an electric circuit is connected to the bar 116 and the other wire 150 is connected to the bar 148. Secured to the U-shaped bracket 118, but insulated therefrom, is an arm 151 to which is secured the wiper-spring 152, which said spring rides upon the bar 148 and thus maintains electrical contact therewith in any position of the knife-holder transversely of the machine. In the construction shown said arm 151 is connected to the bracket 118 by the same stud or bolt 153 that secures the arm 129 to said bracket, and so that said arm 129 is in electrical communication with said arm 151, both of said arms being insulated from the bracket 118, and being thus insulated from the bar 116. The pin 131 carried by the knife-holder is in electrical communication with said bar 116, and it will therefore be seen that whenever said pin comes in contact with either the front or the rear wall of the slot 130 in the arm 129, the electric circuit will be closed, said pin 131 constituting the circuit-closer.

As shown in the drawings, the wire 149 connects with one pole of the battery B. Leading from the other pole of the battery is a wire 154, which may, if desired, lead directly to the electro-magnet E, with which electro-magnet the wire 150 connects. It is preferred, however, to provide means for breaking the electric circuit after it has been closed, and for this purpose the wire 154, instead of leading directly to the electro-magnet, is connected with a binding screw 155 carried by the latch-lever 68. Secured to the frame of the machine is a spring electrode 156 adapted to be engaged by the electrode 155 whenever the latch-lever is moved to engage the clutch 47. A wire 157 connects the electrode 156 with the electro-magnet E. With this construction, as will be seen, whenever the machine is stopped, either automatically or otherwise, the movement of the latch-lever 68 to the left in Fig. 4 will serve to move the electrode 155 out of contact with the electrode 156, thereby breaking the circuit. It will be understood that the electrode 156 is insulated from the frame of the machine.

The armature 158 of the electro-magnet E is pivoted at 159 to the frame of the machine, and the outer end of said armature is connected by a link 160 to the arm 104 of the rock-shaft 105.

With the above construction it will be seen that the electric circuit will be closed whenever the pin 131 comes in contact with either wall of the slot 130, as when the knife leaves the race, or when the knife projects through the back of the fabric, and that when said circuit is closed and the electro-magnet E thereby energized, the pull of the armature 158 will move the link 160 up-

ward, and thereby move the toe 106 out from beneath the tappet 107, as in the case of the mechanical stop motion above described, and thereby cause the clutch 47 to be automatically thrown out, and the brake 49 to be automatically applied.

It will thus be seen that the machine is provided with two automatic stop motions, one a mechanical stop motion adapted to 10 be operated by the bunch or seam in the fabric, and the other an electric stop motion adapted to be operated by the knife or knife-holder, whenever the knife becomes displaced from its proper position in the 15 race to be cut. It will be further noted that these two stop motions are connected together, and so that each of said stop motions will serve to operate the clutch 47 and the brake 59. By reason of this connection of the two stop motions it is necessary or desirable to provide means whereby the operation of one stop motion will not be prevented by the other, and whereby, on the 20 other hand, the operation of one stop motion will not operate the other. As shown in the drawings, the link 160 is provided with an elongated slot for the reception of the pin 161, which serves to connect said link with the arm 104. So also, the link 103 25 is provided with a slot for the reception of the pin 162, which connects said link with the lever 100. With this construction, as will be seen, the arm 104 of the rock-shaft 106 may be moved upward by the link 103, 30 under the action of the mechanical stop-motion, without any corresponding movement of the link 160, whereas, on the other hand, said arm 104 may be moved upward by the link 160, under the action of the electric stop motion, without any corresponding 35 movement of the link 103.

It will be seen that in the machine above described the knife forms an operative part of the machine, and so that the machine 40 thereby becomes entirely automatic in its operation, there being nothing for the operator to do with respect to the cutting of the fabric except to enter the knife in the proper race at the commencement of the cutting 45 operation.

It will be further seen that with the construction shown, while the machine is thus entirely automatic, the liability of injury to the fabric is reduced to a minimum. If 50 the knife flies out of the race, or penetrates the back of the fabric, or enters a wrong race, the machine will be automatically stopped, while in case the knife flies out of the race it will be moved in a direction to 55 carry it above that portion of the fabric which has already been cut where it can do no harm, even if it comes in contact with the fabric before the machine is stopped.

As will be seen, the mounting of the knife 60 so that it has a forward and back yielding or

give and take movement, according to the amount of thrust exerted upon it by the fabric or the amount of resistance offered by the fabric, as well as its capacity to follow any irregularities in the races, causes 70 the operation of cutting with the knife thus incorporated as a part of the machine to closely resemble the operation of cutting when the knife is held by the operator, and renders the automatic cutting of the fabric, 75 not only possible, but entirely practical, which has not heretofore been the case.

In addition to the stop motion for automatically stopping the machine in case of any accidental displacement of the knife, 80 the machine also embodies a stop motion for automatically stopping the machine when the seam or bunch in the fabric approaches the knife, and these two stop motions are so arranged and combined that the operation of one stop motion will not be interfered with by the other, and that each may be operated without operating the other.

By operating the reversing clutch by a 90 foot-treadle, said reversing clutch may be held in engagement during the reverse feed of the fabric by the foot of the operator, thereby leaving both hands free to manipulate the cloth or the knife, or to perform any other operations that may be necessary or desirable during such reverse feed. Such arrangement also makes it possible to operate both the main clutch and the reversing clutch by one and the same device, with 95 means for determining which of said clutches is to be operated thereby, which is a further convenience in the practical operation of the machine.

I am aware that in machines for cutting 105 pile fabrics, in which a series of rotary cutters arranged to cut the pile from the outside of the race are employed, such rotary cutters have been mounted on and have formed a part of the machine, but such machines are of a different type from that to 110 which my invention relates, operate in a different manner, and are not adapted for the cutting of velvets.

My invention relates to that type of pile 115 cutting machines in connection with which a knife, as distinguished from a rotary cutter, is employed, such knife being adapted to enter the race and travel therein, and so as to cut the pile from the inside of the 120 race, and which knife has heretofore, so far as I am aware, been held or guided by the operator during the operation of cutting.

What I claim as my invention and desire 125 to secure by Letters Patent is:

1. In a pile cutting machine, the combination, with means for feeding the fabric through the machine, of a knife adapted to enter the race of the fabric, and a knife- 130

- holder mounted to have more or less forward and back movement to enable said knife to accommodate itself to the varying conditions presented.
5. 2. In a pile cutting machine, the combination, with means for feeding the fabric through the machine, of a knife adapted to enter the race of the fabric, and a knife-holder mounted to normally yield in the direction of the thrust exerted thereon by the fabric.
10. 3. In a pile cutting machine, the combination, with means for feeding the fabric through the machine, of a knife adapted to enter the race of the fabric, and a spring for holding said knife to its work against the thrust of the fabric.
15. 4. In a pile cutting machine, the combination, with means for feeding the fabric through the machine, of a knife adapted to enter the race of the fabric, a spring for holding said knife to its work, and means for adjusting the tension of said spring.
20. 5. In a pile cutting machine, the combination, with means for feeding the fabric through the machine, of a knife adapted to enter the race of the fabric, and means for moving said knife to one side, in case the knife flies out of the race.
25. 6. In a pile cutting machine, the combination, with means for feeding the fabric through the machine, of a knife adapted to enter the race of the fabric, and a spring adapted to move the knife to one side in case the knife flies out of the race.
30. 7. A knife-holder for pile cutting machines constructed in two parts, with one of said parts pivotally mounted in the other part, and said two parts connected together by a spring adapted to turn one of said parts with relation to the other.
35. 8. A knife-holder for pile cutting machines constructed in two parts, one part of said knife-holder being pivoted to swing about a horizontal axis, and the other part which receives the knife-shank being pivoted to swing about a vertical axis.
40. 9. A knife-holder for pile cutting machines constructed in two parts, one part of said knife-holder being pivotally mounted on the machine to swing about a horizontal axis, and the other part being pivotally mounted in said first part which receives the knife-shank.
45. 10. A knife-holder for pile cutting machines constructed in two parts, one part of said knife-holder being adapted to be pivotally mounted on the machine to swing about a horizontal axis, and the other part of said knife-holder being pivotally mounted in said first part to swing about a vertical axis.
50. 11. The combination, with a knife-holder constructed in two parts and having one part of said knife-holder pivotally mount-
- ed in the other part, of a spring turning said pivoted part on its pivot in one direction, and means for turning said pivoted part in the opposite direction against the action of said spring.
55. 12. The combination, with a knife-holder, of means for pivotally mounting said knife-holder to swing about a horizontal axis, and means for limiting such swinging movement.
60. 13. The combination, with a bar extending crosswise of the machine, of a sleeve adapted to slide on said bar, a knife-holder, and means for pivotally connecting said knife-holder with said sleeve to swing about a horizontal axis.
65. 14. The combination, with a bar extending crosswise of the machine, of a sleeve adapted to slide on said bar, a bracket extending from said sleeve, and a knife-holder pivoted in said bracket to swing about a horizontal axis.
70. 15. The combination, with a bar extending crosswise of the machine, of a sleeve adapted to slide on said bar, a bracket extending from said sleeve, a knife-holder pivoted in said bracket, and means for limiting the movement of said knife-holder about its pivot.
75. 16. The combination, with a bar extending crosswise of the machine, of a sleeve adapted to slide on said bar, a knife-holder, means for pivotally connecting said knife-holder with said sleeve to swing about a horizontal axis, and means for preventing the turning of said knife-holder about its pivot.
80. 17. The combination, with a bar extending crosswise of the machine, of a sleeve adapted to slide on said bar, a knife-holder pivotally mounted on said sleeve, a second sleeve adapted to turn on said first sleeve, and means operated by said second sleeve for preventing the turning of said knife-holder about its pivot.
85. 18. The combination, with a bar extending crosswise of the machine, of a sleeve adapted to slide on said bar, a knife-holder pivotally mounted on said sleeve, a second sleeve adapted to turn on said first sleeve, a pin projecting from said second sleeve and adapted to engage a projection of said knife-holder to prevent the same from turning on its pivot.
90. 19. In a pile cutting machine, the combination of a feed-roll, a drag-roll and an idler roll for the fabric located between said feed-roll and said drag-roll and serving to locate the fabric for presentation to the knife.
95. 20. In a pile cutting machine, the combination of a feed-roll, a drag-roll, and two idler rolls for the fabric located in front of and in proximity to said drag-roll, from one of which idler rolls the fabric passes in an inclined direction to said feed-roll.

21. In a pile cutting machine, the combination of a feed-roll, a drag-roll, an idler roll located in proximity to said drag-roll and around which the fabric passes before passing to said drag-roll, a second idler roll located in proximity to said first mentioned idler roll and around which the fabric passes after moving said drag-roll, whereby the fabric will be caused to pass around a large part of the periphery of said drag-roll, and a third idler roll from which the fabric passes in an inclined direction to said feed-roll. 5 70
22. In a pile cutting machine, the combination of a feed-roll, a drag-roll, an idler roll located in proximity to said drag-roll and around which the fabric passes before passing to said drag-roll, a second idler roll located in proximity to said first mentioned idler roll and around which the fabric passes after leaving said drag-roll, both of said idler rolls being located between said feed-roll and said drag-roll, whereby the fabric will be caused to pass around a large part of the periphery of said drag-roll, said drag-roll being a plain steel roll. 10 75
23. In a pile cutting machine, the combination of a feed-roll, a drag-roll of larger diameter than said feed-roll, and means for driving said drag-roll in the reverse direction for the reverse feed of the fabric. 15 80
24. In a pile cutting machine, the combination of a feed-roll, a drag-roll of larger diameter than said feed-roll, means for disconnecting said feed-roll, and means for driving said drag-roll in the reverse direction for the reverse feed of the fabric. 20 85
25. In a pile cutting machine, the combination of a feed-roll, a drag-roll of larger diameter than said feed-roll, and means for driving said drag-roll in the reverse direction at a reduced speed. 25 90
26. In a pile cutting machine, the combination of a feed-roll, a drag-roll, and two supplemental driven feed-rolls, around one of which supplemental feed-rolls the fabric passes on its way to said drag-roll, and around the other of which supplemental feed-rolls the fabric passes after it leaves the main feed-roll. 30 95
27. In a pile cutting machine, the combination of a feed-roll, a drag-roll, and a supplemental feed-roll located at the rear of said drag-roll. 35 100
28. In a pile cutting machine, the combination of a feed-roll, a drag-roll, and a supplemental feed-roll located at the rear of said drag-roll and driven from said drag-roll. 40 105
29. In a pile cutting machine, the combination of a feed-roll, a drag-roll, and two supplemental feed-rolls, both of said supplemental feed-rolls being driven from said drag-roll. 45 110
30. In a pile cutting machine, the combination of a feed-roll, a drag-roll, and two supplemental feed-rolls, both of said supplemental feed-rolls being driven from said drag-roll. 50 115
- supplemental feed-rolls, both of said supplemental feed-rolls being driven from said drag-roll, but at different speeds. 55 120
31. In a pile cutting machine, the combination of a feed-roll, a drag-roll, a supplemental feed-roll located at the rear of said drag-roll, and means for rotating said supplemental feed-roll at a slower speed than said drag-roll. 60 125
32. In a pile cutting machine, the combination of a feed-roll, a supplemental feed-roll around which the fabric passes after it leaves said main feed-roll, and means for rotating said supplemental feed-roll at a higher speed than said main feed-roll. 65 130
33. In a pile cutting machine, the combination of a feed-roll, a supplemental feed-roll around which the fabric passes after it leaves said main feed-roll, and means for rotating said supplemental feed-roll at a higher speed than said main feed-roll during the forward feed of the fabric and at a slower speed during the reverse feed of the fabric. 70 135
34. In a pile cutting machine, the combination of a feed-roll, a supplemental feed-roll, and means for driving said supplemental feed-roll during the forward feed of the fabric and causing said roll to run idle during the reverse feed of the fabric. 75 140
35. In a pile cutting machine, the combination of a feed-roll, a supplemental feed-roll, and a pawl and ratchet for driving said supplemental feed-roll during the forward feed of the fabric. 80 145
36. In a pile cutting machine, the combination of a feed-roll, a drag-roll, and a supplemental feed-roll, said supplemental feed-roll being driven from said drag-roll by a pawl and ratchet connection during the forward feed of the fabric. 85 150
37. In a pile cutting machine, the combination of a feed-roll, a supplemental feed-roll, means for driving said supplemental feed-roll during the forward feed of the fabric, and means for putting a drag on said roll during the reverse feed of the fabric. 90 155
38. In a pile cutting machine, the combination of a feed-roll, a supplemental feed-roll, means for driving said supplemental feed-roll during the forward feed of the fabric, and means for applying a brake to said roll during the reverse feed of the fabric. 95 160
39. In a pile cutting machine, the combination of a feed-roll, a supplemental feed-roll, means for driving said supplemental feed-roll during the forward feed of the fabric, and means for automatically applying a brake to said roll when the machine is reversed. 100 165
40. In a pile cutting machine, the combination of a feed-roll, a supplemental feed-roll, a pawl and ratchet for driving said supplemental feed-roll during the forward feed of the fabric, and means for applying a brake to said roll during the reverse feed of the fabric. 105 170

feed of the fabric, and means for applying a brake to said roll during the reverse feed of the fabric.

41. In a pile cutting machine, the combination of a feed-roll, a supplemental feed-roll, a pawl and ratchet for driving said supplemental feed-roll during the forward feed of the fabric, and a brake adapted to act on said supplemental feed-roll, the application of said brake being controlled by the mechanism for effecting the reverse feed of the fabric.

42. In a pile cutting machine, the combination of a feed-roll, a supplemental feed-roll, a pawl and ratchet for driving said supplemental feed-roll during the forward feed of the fabric, a brake adapted to act on said supplemental feed-roll, and a spring adapted to operate said brake, the operation of said 20 spring to apply the brake being controlled by the mechanism for effecting the reverse feed of the fabric.

43. In a pile cutting machine, the combination with a feed-roll and a drag-roll of a 25 main clutch, a reversing clutch, and means adapted to operate either one of said clutches as may be desired.

44. In a pile cutting machine, the combination with a feed-roll and a drag-roll of a 30 main clutch, a reversing clutch, and a foot-treadle adapted to operate either one of said clutches.

45. In a pile cutting machine, the combination with a feed-roll and a drag-roll of a 35 main clutch, a reversing clutch, means for operating either one of said clutches, and means for determining which of said clutches shall be operated.

46. In a pile cutting machine, the combination with a feed-roll and a drag-roll of a main clutch, a reversing clutch, a foot-treadle for operating either one of said 45 clutches, and a hand-lever for determining which of said clutches is to be operated by said foot-treadle.

47. In a pile cutting machine, the combination with a feed-roll and a drag-roll of a main clutch-lever, a reversing clutch-lever, a rock-shaft, a sliding rod carried by said 50 rock-shaft and adapted to operate one or the other of said clutch-levers, and means for sliding said rod.

48. In a pile cutting machine, the combination with a feed-roll and a drag-roll of a 55 main clutch-lever, a reversing clutch-lever, a sliding rod carried by said rock-shaft and adapted to operate one or the other of said clutch-levers, a hand-lever for sliding said rod, and a foot-treadle for rocking said 60 rock-shaft.

49. In a pile cutting machine, the combination of a knife adapted to enter a race of the fabric, and a stop motion adapted to be operated by a forward or backward move-

ment of said knife produced by a reduced 65 or an increased thrust of the fabric thereon.

50. In a pile cutting machine, the combination of a knife adapted to enter a race of the fabric, and a stop motion adapted to be operated by a forward movement of said 70 knife produced by a reduced thrust of the fabric thereon.

51. In a pile cutting machine, the combination of a knife adapted to enter a race of the fabric, and a stop motion adapted to 75 be operated by a backward movement of said knife produced by an increased thrust of the fabric thereon without turning said knife.

52. In a pile cutting machine, the combination of a knife adapted to enter a race of the fabric, and a stop motion adapted to be operated by a backward movement of said 80 knife produced by the thrust of the fabric thereon when the knife enters a slip race. 85

53. In a pile cutting machine, the combination of a knife adapted to enter the race of the fabric, a pivoted knife-holder, a spring 90 acting upon said pivoted knife holder against the thrust of the fabric, and a stop motion adapted to be operated by the turning of said knife-holder on its pivot.

54. In a pile cutting machine, the combination of a knife adapted to enter a race of the fabric, a pivoted knife-holder, a spring 95 acting upon said pivoted knife-holder against the thrust of the fabric, and a stop motion adapted to be operated by the turning of said knife-holder on its pivot, either by the increased thrust of the fabric or by 100 the action of said spring.

55. In a pile cutting machine, the combination of a knife adapted to enter the race of the fabric, a stop motion adapted to be operated by said knife when displaced from 105 its normal position, a second stop motion adapted to be operated by a bunch or seam in the fabric, and a movable member common to both of said stop motions.

56. In a pile cutting machine, the combination of a knife adapted to enter the race of the fabric, a stop motion adapted to be operated by said knife when displaced from its normal position, and a second stop motion adapted to be operated by a bunch or 115 seam in the fabric, said two stop motions being connected to operate each independent of the other.

57. In a pile cutting machine, the combination of a knife adapted to enter the race 120 of the fabric, means for feeding the fabric through the machine, a clutch for controlling the feed of the fabric, a stop motion adapted to be operated by said knife to throw out said clutch, and a second stop motion adapted to be operated by a bunch 125 or seam in the fabric to throw out said clutch.

58. In a pile cutting machine, the combination of a knife adapted to enter a race of the fabric, means for feeding the fabric through the machine, a clutch for controlling the feed of the fabric, a stop motion adapted to be operated by said knife to throw out said clutch, a second stop motion adapted to be operated by a bunch or seam in the fabric to throw out said clutch, and connections between said stop motions having lost motion therein.

59. In a pile cutting machine, the combination of a knife adapted to enter the race of the fabric, an electric stop motion adapted to be operated by said knife when displaced from its normal position, a mechanical stop motion adapted to be operated by a

bunch or seam in the fabric, and a movable member common to both of said stop motions.

60. In a pile cutting machine, the combination of a knife adapted to enter the race of the fabric, an electric stop motion adapted to be operated by said knife when displaced from its normal position, and a mechanical stop motion adapted to be operated by a bunch or seam in the fabric, said two stop motions being connected to operate each independent of the other.

ARTHUR MORTON.
